Primary Examiner — Ian Simmons*Assistant Examiner* — Charles Hanson(74) *Attorney, Agent, or Firm* — Seager, Tufte & Wickhem LLC**CLAIM**

An ornamental design for a spinal rod connector, as shown and described.

DESCRIPTION

FIG. 1 is a perspective view of a spinal rod connector to the present invention; and,

FIG. 2 is a side plan view of the spinal rod connector of FIG. 1.

Those portions shown in broken lines are for illustrative purposes only and form no part of the claimed design.
